US00D939509S

(12) **United States Design Patent** (10) **Patent No.:** **US D939,509 S**
(45) **Date of Patent:** ** *Dec. 28, 2021

(54) **HOUSING PLATE**

(71) Applicant: **Apple Inc.**, Cupertino, CA (US)

(72) Inventors: **Richard Hung Minh Dinh**, San Jose, CA (US); **Richard P. Howarth**, San Francisco, CA (US); **Scott A. Myers**, San Francisco, CA (US); **David A. Pakula**, San Francisco, CA (US); **Tang Yew Tan**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/658,273**

(22) Filed: **Jul. 30, 2018**

Related U.S. Application Data

(60) Continuation of application No. 29/554,625, filed on Feb. 12, 2016, now Pat. No. Des. 824,389, which is a continuation of application No. 29/503,544, filed on Sep. 26, 2014, now Pat. No. Des. 749,590, which is a continuation of application No. 29/429,885, filed on Aug. 17, 2012, now Pat. No. Des. 714,294, which is a continuation of application No. 29/363,173, filed on Jun. 5, 2010, now Pat. No. Des. 666,202, which is a continuation of application No. 13/561,567, filed on Jul. 30, 2012, now Pat. No. 9,867,301, which is a division of application No. 12/794,467, filed on Jun. 4, 2010, now Pat. No. 8,264,837.

(57) **CLAIM**

The ornamental design for a housing plate, as shown and described.

DESCRIPTION

FIG. 1 is a bottom rear perspective view of a housing plate showing the claimed design;

FIG. 2 is a top rear perspective view thereof;

FIG. 3 is a bottom front perspective view thereof;

FIG. 4 is a top front perspective view thereof;

FIG. 5 is a rear view thereof;

FIG. 6 is a front view thereof;

FIG. 7 is a bottom view thereof;

FIG. 8 is top view thereof;

FIG. 9 is a left side view thereof; and,

FIG. 10 is a right side view thereof.

The shade lines in the figures show contour and not surface ornamentation.

The broken lines in the figures show portions of the housing plate that form no part of the claimed design.

1 Claim, 8 Drawing Sheets
